CLAIM

The ornamental design for a starter bottle, as shown and described.

DESCRIPTION

FIG. 1 is a perspective view of a first embodiment of a starter bottle showing our new design;

FIG. 2 is a front view thereof;

FIG. 3 is a left side view thereof; the right side view being a mirror image thereof;

FIG. 4 is a rear view thereof;

FIG. 5 is a top view thereof;

FIG. 6 is a bottom view thereof;

FIG. 7 is a a perspective view of a second embodiment of a starter bottle showing our new design;

FIG. 8 is a front view thereof;

FIG. 9 is a left side view thereof; the right side view being a mirror image thereof;

FIG. 10 is a rear view thereof;

FIG. 11 is a top view thereof;

FIG. 12 is a bottom view thereof;

FIG. 13 is a perspective view of a third embodiment of a starter bottle showing our new design;

FIG. 14 is a front view thereof;

FIG. 15 is a left side view thereof; the right side view being a mirror image thereof;

FIG. 16 is a rear view thereof;

FIG. 17 is a top view thereof;

FIG. 18 is a bottom view thereof;

FIG. 19 is a perspective view of a fourth embodiment of a starter bottle showing our new design;

FIG. 20 is a front view thereof;

FIG. 21 is a left side view thereof; the right side view being a mirror image thereof;

FIG. 22 is a rear view thereof;

FIG. 23 is a top view thereof; and,

FIG. 24 is a bottom view thereof.

The oval-shaped broken lines showing planar areas in front and/or rear portions of the bottle in FIGS. 1-24; the oval-shaped broken lines showing a central portion of a bottom surface of the bottle in FIGS. 6, 12, 18, and 24; and the broken lines showing a threaded top portion of the bottle in FIGS. 1-5, 7-11, 13-17 and 19-23; define the bounds of the claimed design and/or disclose the environment related to the claimed design, and therefore form no part of the claimed design. The stippling appearing in the drawings is provided to show shading and does not represent any particular material, color, pattern, texture, or surface.
